UNITED STATES PATENT OFFICE.

CHARLES MEHLIN, OF FORT LEE, NEW JERSEY.

PIANO CONSTRUCTION.

Application filed August 16, 1926. Serial No. 129,350.

This invention relates in general to a piano construction and has for an object the provision of a sound board construction and arrangement of increased strength and durability and improved tone quality.

An important object of the invention is the provision of a sound board that will not sag or warp and thereby lose its vibrating and tone qualities.

Another important object of the invention is to provide a sound board for a piano that is reinforced or provided with means for relieving the sound board of the normal pressure of the strings and bridge so that the sound board will be substantially free to vibrate or will freely vibrate in response to vibrations of the strings so that the tone of the piano will be of longer duration and will be more full, more clear, and of greater volume and carrying power.

Another important object of the invention is to provide a piano in which the sound board is formed to extend equal distances to each side of the main string bridge and such a device in which the sound board is formed substantially in accordance with the human tone cavity.

Another important object of the invention is to provide a tone chamber beneath the sound board of a piano that is formed to amplify the tone generated by the vibration of the strings in proportion to the pitch of the string so that the tones generated by the higher pitched and weaker strings will be amplified in proportion to the weakness or pitch of the string and such a device that is formed substantially in accordance with the human tone cavity.

Numerous other objects and advantages of the invention will be apparent as it is better understood from the following description which taken in connection with the accompanying drawings illustrates a preferred embodiment thereof.

Referring to the drawings:

Figure 1 is a plan view of a piano with parts removed and embodying my invention;

Fig. 2 is a sectional view taken substantially on line 2—2 in Fig. 1; and

Fig. 3 is a further enlarged view taken substantially on line 3—3 in Fig. 2 and showing the sound board and two stiffening ribs in cross section.

To illustrate my invention I have shown a

piano frame 11, a sound board supporting frame or rim 12, a sound board 13, a string frame 14 and bridges 15.

The frame 11 may be of any suitable form and material such as that of an upright or grand piano, and I have shown the frame of a grand piano, merely to illustrate my invention. The supporting frame or rim 12, the sound board 13, the supporting frame 14 and bridges 15 are also constructed in accordance with the design of the piano, and may be of any suitable size. The sound board 13 is preferably crowned slightly as shown (Fig. 2) and stiffening ribs 16 are provided that may be attached to the sound board in any suitable manner, such as by glue or with pegs or the like. The stiffening ribs 16 may extend across the sound board in any desired direction and are preferably arranged at right angles to the grain of the sound board. They are preferably of sufficient length to extend entirely across the sound board wherever used, but it will be noted that they may be somewhat shorter if desired. The ends 17 of the stiffening ribs 16 are preferably seated in the supporting frame or rim 12 as at 18 (Fig. 2) to provide bearings for the ribs.

In accordance with my invention the ribs 16 are of a relatively large cross sectional area at or adjacent their ends and of a reduced cross sectional area intermediate their ends. That is, the cross sectional area is preferably the least at or beneath the long bridge or at the center of the board and the greatest at the supports. This may be accomplished by forming the ribs of uniform width and varied thickness or of uniform thickness and varied width. In the present instance however, I have shown the upper surface 19 of the ribs formed to fit the sound board 13 and the lower surface 21 of the ribs 16 curved on a somewhat smaller radius so that the thickness is gradually increased as the distance from the center of the board is gradually increased or so that the thickness gradually decreases as the distance from the support gradually increases. The difference between the minimum and maximum thickness or cross sectional area should not be so great however, as to provide a rigid construction, such as might prevent or materially reduce the vibrations, and is determined by the length of span and the normal pressure of the strings. It is an object of the inven-

tion to provide a balanced sound board that will yield to vibrations equally on each side of the bridge and this regardless of whether or not the bridge is located at the center of the sound board and to provide a board in which the bridge and string pressure is balanced by the strength of the ribs and thus reduce the resistance to vibrations transmitted to the sound board and leave the sound board substantially free to vibrate just as it would if there were no string pressure on the bridge. The thickness of the ribs for this reason is determined by the pressure of the strings and the distance between the sound board supports. In constructing the bridge as shown, one or more bridges 15 may be positioned on the sound board at any position between the supports, and the vibrations transmitted to the sound board through the bridge will be of like strength and character, the tendency being for the board to give at the point of application of the forces, which is at the bridge, and to radiate therefrom. The sound board being substantially free to vibrate will uniformly distribute the vibrations.

It is another important object to provide a tone chamber beneath or adjacent the sound board that is formed substantially in accordance with the human tone cavity in which the cross sectional area beneath each string is in proportion to the vibrating string or to the power of the string to set air in motion so that the correct volume of air or space beneath each string is the amount that the string is able to set in motion to generate a full round tone and such a chamber that will amplify the tones generated by the strings in proportion to the volume of the tone or pitch of the strings so that the small strings having a high pitch and relatively small tone value will be amplified to a high extent and the large strings having a low pitch and a large tone value will be only slightly amplified, or not amplified. To accomplish this the sound board is preferably extended to substantially equal distances on each side of the main string bridge 15 and such distances that are in proportion to the length of the string and a closure member 31 is arranged beneath or adjacent the sound board and spaced therefrom to provide a tone chamber 32. The member 31 may be attached or supported upon the frame 12 in any suitable manner and is formed substantially in accordance with the sound board 13. An opening 33 is provided that may be either in the frames 11 and 12, the sound board 13 or the member 31, for establishing communication between the chamber 32 and the atmosphere. This opening may be of any suitable size and provided with volume control devices of any suitable type if desired. It will be noted that the strings to the right, viewing Fig. 1, are the short and high pitched

strings and the strings to the left are the long and low pitched strings and that a section cut through a piano at either of these strings will intersect the chamber 32 and that the cross sectional area of the chamber 70 in the point of intersection is in proportion to the length and pitch of the strings and since the power of the string to set air in motion is also in proportion to the length and size of the string the correct amount of space or 75 air or just the amount that a string will properly control or set in motion is beneath each string and further that since the chamber 32 tapered from a relatively small cross sectional area under the high pitched strings 80 to a relatively large cross sectional area under the low pitched strings, the tones generated by the high pitched strings or by all strings are, or may be, amplified in proportion to the pitch of the string or vibrations. 85

It is thought that the invention and many of its attendant advantages will be understood from the foregoing description, and it will be apparent that various changes may be made in the form, construction and arrangement of the parts without departing from the spirit and scope of the invention, or sacrificing all of its material advantages, the form hereinbefore described being merely 95 a preferred embodiment thereof.

I claim:

1. In a piano, the combination of a curved sound board, a support for the said board to support its periphery and bracing ribs extending under the board and supported in the 100 sound board supports, the ribs being of uniform width and curved to decreasing thickness adjacent the bridge.

2. In a piano, the combination of a curved sound board, a support therefor engaging its edges, and bracing ribs extending under the sound board in contact therewith, the ribs having bearings in and being supported by the sound board supports, the ribs curving to a diminished cross-sectional area adjacent the 110 bridge.

3. In a piano, the combination of a string bridge, a curved sound board to support said bridge, a rim adapted to support the edges of the sound board, and stiffening ribs seated in the rim, the ribs being of uniform width and curved to a diminished thickness adjacent the bridge.

4. In a piano, the combination of strings, a string bridge arranged in support thereunder, a curved sound board for the strings supported by the bridge, a sound board support engaging the edges of the board and stiffening ribs extending under the sound board, the ribs being curved to diminished cross-sectional area adjacent the bridge and supported by bearings in the sound bridge support.

5. In a piano, the combination of strings, a string bridge therefor, the bridge being located near the curved center of the ribs, a 130

curved sound board supporting the bridge, a sound board support engaging the edges thereof, and rims of varying cross-sectional area stiffening and supporting the board 5 borne in the board supports, the cross-sectional area being varied by two curved surfaces, the greater area being at the bearings and the lesser adjacent the bridge.

6. In a piano, the combination of strings, a 10 bridge therefor, a curved sound board supported at its edges, curved stiffening ribs for the sound board having two surfaces of unequal curvature and a sound chamber thereunder, the chamber being open to the air and 15 having a non-uniform cross-sectional area.

7. In a piano, the combination of a curved sound board, strings arranged thereover, means to transmit vibrations of the strings to the board, a closure member beneath the sound 20 board and spaced therefrom to provide the

tone chamber, the tone chamber being of non-uniform cross-sectional area.

8. In a piano, the combination of strings, a string bridge thereunder, a curved sound board, a support for the board at its edges, 25 stiffening ribs for the board, the said ribs being supported in bearings in the sound board it supports and having a varying cross-sectional area, the greater area being at the bearings and the lesser adjacent the bridge, 30 the ribs having a uniform width and the depth varying between two unlike curved surfaces, and a closure member spaced from and under the sound board providing a tone chamber, the cross-sectional area of the tone chamber at 35 any point therein varying in proportion to the vibration value of a string thereover, the said tone chamber being open to the air.

CHARLES MEHLIN.
